UNITED STATES PATENT OFFICE

CHARLES SCHELL, OF CINCINNATI, OHIO, ASSIGNOR TO SCHELL LEATHER GOODS COMPANY, OF CINCINNATI, OHIO, A FIRM COMPOSED OF CHARLES SCHELL AND ALBERT M. SCHELL

BRIEF CASE

Application filed February 17, 1930. Serial No. 428,960.

This invention relates to a brief case.

An object of the invention is to provide a case having improved means for adjustment of the flap.

5 Another object is to provide a case having an improved form of support strap.

Another object is to provide a case comprising certain new and improved details.

These objects are attained by the means 10 described herein and set forth in the accompanying drawings, in which:

Fig. 1 is a front elevational view of a brief case of the present invention, the flap portion thereof being shown in an upright, open 15 position.

Fig. 2 is a view taken on line 2—2 of Fig. 1.

The body of the brief case comprises the usual front 3 and back 4 having the partitions 5 positioned therebetween, all said parts being joined along their bottom and sides by the web portions 6.

20 The flap 7, having a suitable handle 31 thereon, may be an integral extension of back 4 and in the preferred construction has the central portion 8 of its lon-

25 gitudinal edge projecting beyond the adjacent portions of said edge. A strengthening piece 9 may be secured to the under face of the outer portion of flap 7. A stiffening rib 190, is secured transversely of the top or

30 arch portion of flap 7, on the under surface thereof. A headed stud 20 is suitably secured to the rib 190 centrally thereof. A strip 10 has its side edges and its upper end

edge 32, secured to the outer surface of flap 35 7, and extends centrally and vertically of the flap from the edge of portion 8 to the top of the face portion of the flap. The open end 11 of the strip or sheath member 10 is adapted to receive a strap 12, one end 13 of which

40 passes through a slit 14 provided in flap 7 beneath the strip 10. End 13 has a plurality of perforations 15 therein, each perforation having a communicating slit 16 in its edge.

The opposite end 17 of strap 12 projects from 45 the end 11 of the sheath member 10 and is adapted to have a suitable lock member 18 fastened thereon.

Perforations 15 of strap 12 are adapted to receive the shank of stud 20. The head of stud 20 is larger than the perforations 15 but

due to the enlargement of the perforations made possible by the slits 16, the head may be passed therethrough and afterwards is not readily withdrawn, whereby accidental removal is precluded. End 13 of strap 12 is 55 allowed to project downwardly into the case and normally lies in abutment against the inner face of back 4. The projection of end 17 from sheath member 10 may be increased or decreased by changing stud 20 from one to 60 another of perforations 15. By this means proper cooperation of lock 18 with the lock-element 19 secured to the front 3 of the case, is permitted whether the case is filled to the limit or only partially filled, and strain otherwise resulting from stretching the flap 7 in order to engage the lock members, is entirely 65 obviated.

It is desirable in devices of the present kind 70 to provide straps for supporting the bottom of the brief case. Heretofore, it has been customary to provide straps passing completely around the bag, the buckles being attached to the uppermost ends of the straps at the front of the case. The greater portion 75 of these straps was in reality unnecessary so far as support of the case bottom was concerned, and were, in fact, undesirable as to appearance, and in view of the fact that they readily caught upon projecting objects. 80 These undesirable features are obviated in the support straps 21 and cooperating members of this invention.

An end 22 of each of the two support straps 85 21 is secured to back 4 of the case adjacent the bottom and to one side thereof. Strap 21 passes across the bottom of the case then through a suitable guide 23 adjacent the bottom of front 3, and is thereafter engaged by suitable means, such as buckle 24. Buckle 90 24 may be held by the loop portion of a double strap 25, one section 26 thereof being secured to the outer face of front 3, the other section 27 thereof being secured to the inner face of the front 3, after passing through a perforation 28 in said front. After strap 21 has been engaged by buckle 24, the strap is passed upwardly into an elongated sheath or pocket member 280 secured vertically to the outer face of front 3, the open end 29 of said pocket

95 100

being disposed a short distance above the buckle 24 and covering the greater portion of section 26 of the buckle strap 25. Perforations 30 in the free portion of strap 21 permit adjustment of the strap to the load carried by the brief case. By these means, the requisite amount of support for the case bottom is provided by a minimum of strap elements and at the same time a novel and pleasing appearance is achieved.

What is claimed is:

1. A brief case comprising a flap or cover, said flap having a strap attached thereto and slidable vertically thereof, one end of the strap projecting outwardly of the edge of the flap and adapted to have secured thereto a suitable lock element, the other end of the strap projecting inwardly of the case through a perforation in the flap, and means associated with said inwardly-projecting end for securing the strap in adjusted positions relative to the flap.
2. A brief case comprising straps adapted to support the bottom of the case, said straps being secured at one end thereof to the back of the case adjacent the bottom, fastening means secured to the front of the case adjacent the bottom, the free portions of said straps being adapted to pass across the bottom of the case and to be engaged by said fastening means, and inverted sheath members on the front of the case and adapted each to receive and closely embracing one of the straps after engagement thereof by the fastening means.

3. A brief case comprising straps fixed at one end to the back of the case adjacent the bottom, their free portions being adjustably attachable to the front of the case adjacent the bottom, the straps being adapted to pass across the bottom of the case for supporting said bottom.

4. A brief case comprising a body and a flap portion, a movable member adjustably attached to the flap and adapted to have a lock element secured thereto, straps having one end of each thereof secured to the back of the body adjacent the bottom, their free portions being adapted to pass across the bottom of the body, means on the face of the body adjacent the bottom for adjustably attaching the free portions of said straps thereto, a sleeve member on the face of the flap portion for receiving said movable member, and pocket members on the face of the body for receiving the straps after engagement thereof by said attaching means.

5. In an article of hand luggage the combination of a case body, a flap foldable over the front of the case, sheath members on the flap and front of the case, straps slidable in the inverted sheaths and adapted to be substantially enclosed thereby and fastening elements on the front of the case cooperating with said straps.

6. In an article of hand luggage, a case, a closing flap foldable over the top and front of the case, a strap member extending through the body of the flap whereby one end is disposed within the case and the other end is disposed outside of the case and extending over the edge of the flap, cooperating means on the front of the case and the outer end of the strap for closing the case, sheath means on the flap to slidably house the outer end of the strap and means within the case to adjust the length of the strap.

In testimony whereof, I have hereunto subscribed my name this 8th day of February, 1930.

CHARLES SCHELL.
